UNITED STATES PATENT OFFICE.

WILLIAM J. QUINN, OF COLUMBUS, OHIO, ASSIGNOR TO NATIONAL CHEMICAL COMPANY, OF SYRACUSE, NEW YORK, A CORPORATION OF NEW YORK.

COLLAR-IRONING MACHINE.

1,147,435.

Specification of Letters Patent. Patented July 20, 1915.

Application filed February 18, 1911. Serial No. 609,415.

To all whom it may concern:

Be it known that I, WILLIAM J. QUINN, of Columbus, in the county of Franklin, in the State of Ohio, have invented new and 5 useful Improvements in Collar-Ironing Machines, of which the following, taken in connection with the accompanying drawings, is a full, clear, and exact description.

This invention relates to certain improvements in collar ironing machines of the class 10 set forth in my Patent #792,454 June 13, 1905, except that in the present instance the moving parts are power driven and synchronized so as to repeat the pressing or 15 ironing operation on different collars at regular predetermined intervals.

These machines are particularly adapted 20 for shaping, smoothing and drying folded or turn-over collars and for simultaneously spacing the band and outer portion of the collar a sufficient distance apart to permit a necktie to be readily drawn back and forth in such space in the operation of adjusting the tie and at the same time smoothing or 25 removing any roughness or irregularities from the folded edge of the collar.

The main object of my present invention 30 is to render the operation of shaping, ironing or smoothing the collar practically automatic.

Another object is to enable a plurality of collars to be operated upon at one and the same time so as to increase the output and reduce the cost of the work.

35 A further object is to provide simple means whereby the collar supports will automatically adjust themselves to the shaping heads when forced to their pressing positions in the operation of shaping and 40 smoothing the collars so that all parts of the folds or edges of the collars will be smoothed and shaped alike under uniform pressure.

Other objects and uses will be brought 45 out in the following description:

In the drawings—Figure 1 is a perspective view of a collar shaping and ironing machine embodying the various features of my invention. Fig. 2 is a transverse vertical 50 sectional view through the center of the machine. Fig. 3 is an enlarged sectional view of one of the shaping heads showing the collar support and collar thereon in position for shaping and smoothing. Fig. 4 is a transverse sectional view of one of the collar 55 supports and adjacent portion of the re-

volving carrier on which it is mounted. Fig. 5 is an inverted plan of the pinion and locking disk on the upright shaft showing also the locking dog in section and in dotted lines 60 the adjacent portion of the driving gear by which intermitting rotary motion is imparted to the carrier for the collar supports. Fig. 6 is an inner side elevation of the cam and connections for raising and lowering the 65 carrier supporting shaft, the operating lever being shown in section and portions of the worm gear in elevation. Fig. 7 is a perspective view of the detached belt shifting device. 70

This machine comprises a main supporting frame —1— having a suitable table top or tray —2— upon which the collars to be operated upon may be temporarily supported, said tray being provided near one 75 end with a smooth cylindrical tube or chute —3— through which the finished collars may be passed into an underlying receptacle not shown, the chute serving to additionally shape the collars while passing there- 80

A main driving shaft —4— is journaled in a horizontal position in suitable bearings on the rear portion of the main supporting frame —1— some distance below the table 85 top or tray —2— and is provided with tight and loose pulleys —5— and —6— adapted to be connected by a belt to any available source of power not necessary to herein illustrate or describe. 90

The belt, not shown, may be shifted at will by means of a shifting rod —7— and suitable connections with a pedal lever —8— or hand lever —9— so that the shifting of the belt may be effected either by the foot or 95 by hand.

Secured to the shaft —4— is a worm —10— meshing with a worm gear —11— on a forwardly and rearwardly extending horizontal shaft —12— which is also journaled 100 in suitable bearings on the main supporting frame just above the main driving shaft —4— and is provided with a cam —13— and mutilated gear —14— for intermittently reciprocating and rotating an upright shaft 105 —15— and carrier —16— having a plurality of pairs of collar supports —17—.

The means for transmitting reciprocatory motion from the cam —13— to the shaft —15— preferably consists of a rock arm 110 —18— operatively connected to the cam by means of a roller bearing —19— and also

connected by a link —20— to an underlying lever —21—, said rock arm and lever being suitably fulcrumed on the main supporting frame as best seen in Figs. —2— 5 and —6—. The front end of the lever 21 is interposed between a fixed collar —22— and a yielding collar —23— on the upright shaft —15— so as to move the carrier and its collar supports —17— to their pressing 10 positions under yielding pressure of a spring —24— which is interposed between the yielding collar —23— and an adjusting nut —25— on said shaft. This nut together with the lock nut —26— are engaged with 15 the threaded portion —27— of the upright shaft —15— and serve to vary the tension of the spring —24— as may be required. The gear —14— meshes with a mutilated pinion —28— which is journaled in a suitable bearing —29— on the main supporting frame 20 constituting a part of the table top —2— and is held against endwise movement by a shoulder —30— and a collar —31— engaging lower and upper sides of the bearing 25 —29—. The pinion —28— is mounted upon the shaft —15—, a portion of which is angular in cross section and passes through a corresponding central opening through the pinion so as to be free to reciprocate vertically 30 through the pinion and at the same time to be rotated by said pinion for rotating the carrier —16—. The gears —14— and —28— are mutilated in such manner that each revolution of the gear —14— imparts a half revolution to the pinion —28— 35 and carrier —16— through the medium of the shaft —15— so as to alternately move each pair of collar supports into and out of registration with a pair of collar shaping heads —33— presently described.

The pinion —28— is considerably smaller than its driving gear —14— so as to rotate the shaft —15— and carrier —16— for the collar supports at a comparatively quick 45 speed, portions of the gear —14— and pinion —28— having smooth contacting surfaces whereby the pinion is locked against further rotation after each half revolution.

In order that the pinion may be more effectively and positively locked, I provide 50 the shaft —15— with a locking disk —34— preferably integral with the pinion —28—, said disk being provided with diametrically opposite recesses —35— for receiving one 55 end of a pivoted locking bolt —36— which is spring pressed into said recesses by a spring —37— at the end of each half revolution or as soon as the recesses are registered with the locking member —36—.

60 Just prior to the engagement of the teeth of the gear —14— with those of the pinion —28— the locking member —36— is thrown out of engagement with the disk —34— by a cam —38— on the back of the gear —14— 65 so as to free the pinion and permit it to be

actuated a half revolution by the gear or until the opposite recess is brought into registration with the locking member —36—. This action is repeated at each revolution of the gear —14— so as to move each pair of 70 collar supports —17— alternately into registration with the underside of the shaping heads —33—, said operation taking place while the collar supports are depressed in a plane beneath the shaping heads. 75

The cam —13— which is the primary actuator for moving the shaft —15— and carrier —16— vertically is secured to the countershaft —12—, thereby rotating with the gear —14— and is so constructed relative to the gear —14— as to elevate the shaft and carrier to its pressing position to force one pair of the collar supports into the shapers —33—, leaving the other pair of collar supports exposed for the reception of additional collars which may be placed thereon by hand in a manner hereinafter described, the shaft being held against rotation until it is returned downwardly clear from the shapers —33— by which time the cam —38— 90 will have unlocked the pawl —36— and the teeth of the gear —14— will also have engaged and began to rotate the pinion —28— and shaft —15— to shift the other pair of collar supports into registration with the 95 underside of the shapers —33—. In this manner the collar supports are alternately elevated and depressed and then rotated to alternately bring each set of collar supports into pressing engagement with the shapers, 100 always leaving one set exposed to permit the finished collars to be taken off and other collars placed thereon.

The elevation and depression of the shaft together with the carrier —16— and collar supports is comparatively abrupt and accomplished by means of inclined shoulders —39— and —40— formed by recessing a portion of the periphery of the cam —13— which is of sufficient length circumferentially and positioned in such manner as to hold the collar supports clear from the underside of the shapers —33— during a half revolution of the carrier —16— or while the collar supports are changing positions, 115 the remaining portions of the cam —13— being concentric with its axis so as to hold the collars in pressing contact with the shapers —33— during a greater portion of the revolution of the cam —13— and gear 120 —14—.

The operation of the machine may be controlled by either the foot lever —8— or hand lever —9— through the medium of the belt shifting rod —7— which is connected to said levers. 125

The collar supports —17— preferably consist of split bands —41— of thin spring metal mounted at their lower ends on suitable bases —42— preferably of cast metal, 120

leaving the upper edges of the bands —41— free for the reception of collars, and also free to spring radially when entering the shapers —33—. These shapers are identical 5 in construction and each preferably consists of a hollow cast metal ring having a steam chamber adapted to be connected by a pipe —43— to any available source of steam supply for admitting steam thereto for the 10 purpose of heating the shaping head. Secured to and preferably integral with the inner side of the ring is an annular flange —44— forming with the main body an annular groove or socket —45— opening from 15 the underside, the upper side of the groove or socket being smooth and rounding in cross section for the purpose of giving the desired finish to the edge of the collar when the latter is pressed into operative engagement therewith by the upward movement of the collar supporting flange —41—. The inner face of the shaper ring and adjacent face of the flange —44— are polished smooth and preferably tapered or coned upwardly 20 so as to cause the collar to wedge into the groove as it is forced to its pressing position into the head.

Any water of condensation which may accumulate in the steam chamber may be 30 removed through a suitable drain pipe —46— leading from the bottom thereof. The collar supporting members —17— are 35 tiltably mounted upon the rotary carrier —16— to enable them to automatically adjust themselves and thereby press the collars into the groove under uniform pressure at all points and for this purpose are loosely connected to the carrier —16— by swivel or ball and socket joints —47— and suitable 40 tie bolts —48— which extend through apertures in and some distance below the arms of the carrier —16— for receiving coiled springs —49—, the latter being interposed between the heads of the bolt and under- 45 side of the adjacent portion of the carrier —16— to yieldingly hold the collar supports —17— in operative position.

After the collars are properly ironed in the usual manner, their folding edges are 50 slightly moistened after which they are placed by hand upon the exposed forms —41— and at the proper time are shifted from this position into registration with and pressed into the shaping heads —33— 55 until the fold contacts with the base of the grooves —45—, which being heated through the medium of the steam chamber effectively dries and at the same time smoothes any roughened edges or irregularities at the fold. 60 After this operation, the carrier —16— is drawn downwardly by the cam —13— thereby withdrawing the forms —41— with the collars thereon from the heads —33— and shifting such carriers to the front of the machine where the finished collars are removed 65

and placed by hand in the chute —3— from which they are discharged into an underlying receptacle not shown.

The machine may be stopped or started at any time by the operation of either the foot lever —8— or hand lever —9— through the medium of the shifting rod —7— which may be connected in any suitable manner to said levers and is usually provided with radially projecting arms for engaging the 75 opposite edges of the belt by shifting the latter laterally to and from the tight and loose pulleys —5— and —6—.

What I claim is:

1. In a collar-ironing machine of the character described, a collar-shaping head having a circular groove in its under side, a rotary carrier, a circular collar support mounted upon said carrier at one side of its axis and power driven means for intermittently shifting the carrier rotarily a predetermined distance sufficient to move the collar support into and out of registration with the groove in the head and additional power driven means for automatically forcing the collar support into pressing coaction with the head when registered therewith.

2. In a collar-ironing machine of the character described, a shaping-head having a circular groove in its under side, a rotary carrier, circular collar supports mounted on the carrier at opposite sides of its axis of rotation, power driven mechanism intermittently rotating the carrier predetermined degrees for successively registering the collar supports with the groove in the head and additional power driven means for forcing the registering collar support into pressing coaction with the groove in the head.

3. In a collar-ironing machine, a collar-shaping head having a circular groove in its under side, a circular collar support movable laterally into and out of axial alignment with the groove, power driven mechanism intermittently moving the support laterally, and additional means for forcing said support into pressing coaction with the groove in the head when registered therewith.

4. In a collar-ironing machine, a collar-shaping head having a circular groove, a circular collar support movable into and out of axial alignment with the groove, a rotary carrier for the support, means for rotating said carrier intermittently, and means including a spring for yieldingly forcing the collar support into pressing coaction with the groove in the head when registered therewith.

5. In a collar ironing machine of the character described, a collar shaping head and heating means therefor, in combination with a circular collar support, a continuously rotating driving member, and means actuated thereby for intermittently moving the collar support into and out of registration with the

shaping head, and additional means rotating with said driving means for moving the collar support into the shaping head when registered therewith.

- 5 6. In combination with a collar shaping head and heating means therefor, a continuously rotating driving member, a rotary carrier movable axially, a plurality of collar supports mounted on said carrier, means actuated by the driving member for rotating said carrier intermittently to successively register the collar supports with the shaping head, and additional means rotating with the driving member for moving the carrier axially as each collar support is registered with the shaping head.

- 10 7. In a collar shaping machine, a shaping head, a plurality of collar supports and a carrier therefor, a continuously rotating driving shaft, means for transmitting intermitting rotary motion to said carrier to successively register the collar supports with the shaping head, means actuated by the driving shaft for moving said carrier axially 25 when one of the collar supports is registered with the shaping head, additional means for locking the carrier against rotation while the collar support is in the shaping head, and further means for forcing said locking 30 means from its locking position when the collar support is withdrawn from the head.

8. In a collar shaping machine, a shaping head having an annular bearing, means for heating the head, a plurality of collar supports and a rotary carrier therefor, said carrier being movable axially, a continuously rotating driving shaft, means actuated by the shaft for transmitting intermitting rotary motion to the carrier to move 35 the collar supports successively into registration with the head, a cam on the shaft and means actuated by said cam for reciprocating the carrier axially to move the collar support which may register with the 40 head toward and from said annular bearing, and means for locking the carrier against rotation while the registering collar support is coacting with said bearing to press a collar.

- 45 50 9. A collar shaping machine comprising a shaping head having a circular groove in its under side, a rotary carrier movable about a vertical axis at one side of the head, a plurality of collar supports mounted on 55 the carrier at the same distance from the axis as the head, means for rotating the carrier intermittently to successively register the collar supports with the groove in the head, and power driven means for forcing 60 the registering collar supports into pressing coaction with the groove in the head as they are successively registered therewith.

- 65 10. In a collar-ironing machine, a pair of shaping heads having circular grooves in their under sides, separate pairs of circular

collar supports, intermittently movable power driven means for successively registering the collar supports of each pair with the grooves of the heads and for simultaneously positioning one of such pairs at one 70 and the same side of said heads and additional power driven means for forcing the registering collar supports into pressing coaction with the grooves of the heads.

11. In a collar-ironing machine, a pair of 75 horizontally disposed shaping heads arranged side by side and having circular grooves in their under sides, separate pairs of circular collar supports, intermittently movable power driven means for successively registering the collar supports of each pair with the grooves in the heads and for simultaneously positioning one of such pairs at one and the same side of said heads and additional power driven means including 80 a spring for forcing the supports of each pair to their pressing position under yielding pressure as they are successively registered with the grooves of the heads.

12. In a collar ironing machine, a pair of 85 collar shaping heads, a rotary carrier, separate pairs of collar supports mounted on the carrier, said heads and collar supports being disposed at approximately the same 90 distance from the axis of the carrier, mechanism for intermittently rotating the carrier one-half revolution at a time to alternately register each pair of collar supports with the shaping heads, and means for forcing the registering collar supports into pressing 100 coaction with said heads.

13. In a collar-ironing machine, a pair of 105 hollow horizontally disposed collar shaping heads having circular grooves in their under sides, a carrier rotatable in a plane parallel with the grooved sides of the heads, power driven means for intermittently rotating the carrier, separate pairs of circular collar supports movably mounted on the carrier to tilt in all directions, said heads 110 and collar supports being located approximately the same distance from the axis of the carrier, and springs for yieldingly holding the collar supports in an upright position.

14. In a collar-ironing machine, collar shaping heads having a pair of circular grooves disposed side by side in substantially the same plane, a carrier rotatable in a plane intersecting the produced axes of 115 the grooves, separate pairs of circular collar supports mounted on the carrier equidistant from and at opposite sides of its axis corresponding to the distance of the grooves 120 from such axis, and power driven mechanism for intermittently and alternately forcing each pair of collar supports into pressing coaction with the grooves.

15. In a collar ironing machine, a collar shaping element having a collar receiving 125

- groove, a collar supporting element, a rotary carrier, one of said elements mounted upon said carrier, mechanism for rotating said carrier to shift the element mounted thereon into and out of registration with the coacting element, and mechanism for moving one of said elements into pressing coaction with the other when the elements are in registration. 5
- 10 16. In a collar ironing machine, a collar shaping element having a collar receiving groove, a collar supporting element, a rotary carrier, one of said elements mounted upon said carrier, mechanism for rotating said carrier to shift the element mounted thereon into and out of registration with the coacting element, and mechanism for moving said carrier vertically to bring the element mounted thereon into pressing coaction with the other element. 15
17. A collar ironing machine comprising a head having a circular groove, a circular collar support of substantially the same diameter as the groove which it is adapted to enter, said collar support being tiltable relatively to the axis of the head, and means for returning the tilting part into coaxial alignment with the other part when the collar support and head are separate. 20
- 25 18. A collar ironing machine comprising a head having a circular groove, a circular collar support of substantially the same diameter as the groove which it is adapted to enter, one of said parts being tiltable relatively to the axis of the other, and means tending to restore the tilting part into coaxial alignment with the other part. 30
- 35 19. In a collar ironing machine, a head having a circular groove in its underside, a carrier rotatable about an axis at one side of the axis of the groove, a circular collar support mounted upon the carrier a distance from its axis equal to the distance between said axis and that of the groove, power-40
- 45 driven means including mutilated gears for rotating the carrier intermittently to shift the collar support into and out of registration with the circular groove, said mutilated gears having means for holding the carrier against rotation at the end of each intermittent movement, and additional means synchronized with the first named means for moving the carrier axially to force the registering collar support into the groove. 50
- 55 20. In a collar ironing machine, a shaping head having a circular groove in its underside, a rotary carrier having an independent axial movement, a circular collar support on the carrier movable into and out of registration with the groove as the carrier is rotated, means for rotating said carrier intermittently to effect such registration, additional means for stopping the carrier and locking it at the end of each intermittent rotation, and further means for reciprocating the carrier axially while it is locked against rotary movement. 65
21. In a collar shaping and edging machine, a shaping head having a socket, a rotary frame having a plurality of eccentrically positioned hubs, a plurality of collar supports each having an interfitting relation with a respective hub and adapted to be successively moved into and out of registration with said socket in the head upon rotation of said frame, said frame having an axial movement for interfitting a collar support with a collar thereon and the socket to mold the collar, a bolt passed through each collar support and its respective hub, 70 and a spring mounted on each bolt and constituting a resilient connection between the collar supports and frame. 75
22. In a collar ironing machine, a collar support comprising a base having an up-standing flange provided with inwardly projecting pins, a resilient split ring loosely confined within said flange and having openings receiving said pins so that the ring under operating conditions is free to contract with respect to said base and may be removed by contracting the ring sufficiently to disengage the pins with said openings in the ring. 80
- 85 23. In a collar ironing machine, a shaping head having a circular groove in its under side and a collar support movable into and out of the groove and comprising a base having an inwardly projecting radial pin and a circular sheet metal ring divided through one side and having one of its ends provided with an aperture receiving said pin allowing the ring to adjust itself to the groove and permitting said ring to be removed from the base by springing the apertured end inwardly out of engagement with the pin. 90
- 95 24. In a collar molding machine, a shaping head having a socket, a plurality of collar supports and a rotary carrier therefor, 100 said carrier being movable axially, a continuously rotating driving shaft, means actuated by the shaft for transmitting intermitting rotary motion to the carrier to move the collar supports successively into registration with the head, a cam on the shaft, and means actuated by said cam for moving the carrier axially to bring the collar supports into pressing coaction with the socket in said head. 105
- 110 25. In witness whereof I have hereunto set my hand on this 10th day of February 1911. 115
